[57] CLAIM

The ornamental design for a roll-bar pad, as shown and
described.

DESCRIPTION

FIG. 1 is a side elevational view of a roll-bar pad showing
my new design, the opposite side being a mirror image of
that side shown;

FIG. 2 is a top plan view thereof;

FIG. 3 is a bottom plan view thereof;

FIG. 4 is an end elevational view thereof, the opposite end
being a mirror image of the end shown; and.

FIG. 5 is a perspective view thereof.
